To all whom it may concern:

Be it known that I, Sigmund Dawer, a citizen of the United States of America, residing in New York city, in the Borough of Manhattan, county and State of New York, have invented a new, original, and ornamental Design for a Handbag, of which the following is a specification, reference being had to the accompanying drawing, forming part thereof, wherein:

Figure 1 is a front view of a handbag showing my new design.

I claim:

The ornamental design for a handbag, substantially as shown, and described.

SIGMUND DAWER.
